UNITED STATES PATENT OFFICE.

ISAAC HOTALING AND WALTER ALLEN JACOBS, OF ALBANY, NEW YORK; SAID JACOBS
ASSIGNOR TO SAID HOTALING.

DRUGGIST PRESCRIPTION-FILE.

No. 871,089.

Specification of Letters Patent.

Patented Nov. 12, 1907.

Application filed February 23, 1907. Serial No. 358,932.

To all whom it may concern:

Be it known that we, ISAAC HOTALING and WALTER ALLEN JACOBS, citizens of the United States, residing at Albany, in the county of Albany and State of New York, have invented certain new and useful Improvements in Druggist Prescription-Files, of which the following is a specification.

The object of the present invention is to provide an improved device for the filing of prescriptions or data slips of a similar nature in such a manner that they can be instantly found when desired and furthermore so that they can be removed bodily from the file and carried from place to place during the filling of the prescription or similar operation.

15 To this end the invention consists essentially of a case and a plurality of peculiarly designed trays fitting removably within the case, each of said trays being provided with a spring clip for preventing accidental displacement of the data slips held therein.

20 For a full description of the invention and the merits thereof and also to acquire a knowledge of the details of construction and the means for effecting the result, reference is to be had to the following description and accompanying drawings, in which:

25 Figure 1 is a perspective view of a case, some of the trays being shown in position therein. Fig. 2 is a perspective view of one of the filing trays. Fig. 3 is a longitudinal sectional view through the same. Fig. 4 is a perspective view of one of the rear corners of the filing

30 tray. Fig. 5 is a perspective view of one of the front corners of the filing tray. Fig. 6 is a similar view showing the method of bending the parts to form the corners.

Corresponding and like parts are referred to in the following description and indicated in all the views of 35 the drawings by the same reference characters.

The filing case indicated at 1 may be of any conventional construction and is provided with a series of vertical partitions 2, each of which is provided with the horizontal grooves or guide ways 3. These grooves 3 are designed to receive outstanding flanges 4 upon opposite sides of the filing tray 5 in such a manner that the said trays are enabled to have a sliding movement and can be readily placed in position or removed therefrom when found necessary. The filing case 1 is preferably 45 provided with a pair of swinging doors 6 hinged to opposite sides thereof and normally closing the case to exclude the dust and protect the filing trays from injury.

In the specific construction of the filing trays 5 the same are preferably formed from a single piece of sheet material and comprise a bottom 7, oppositely disposed sides 8 the upper edges of which are bent outwardly to form the outstanding flanges 4, and an end 9. Extensions 10 are formed at the rear portions of the sides 8

and these extensions are bent laterally to lie against the rear face of the end 9. The spring clip 11 employed 55 to bear against the data slips 12 and hold the same against accidental displacement is in the nature of a U-shaped member, the two arms of which are coiled adjacent the end 9 to form the spiral springs 13 which operate to normally force the clip against the bottom 60 7 of the filing trays. After being bent to form the said springs 13 the extremities of the two arms of the U-shaped clip 11 extend downwardly along the inside of the end 9, and then pass through the said end and the adjacent extensions 10 when they are bent downwardly against the outer face of the end 9. It will thus be seen that the extremities of the two arms of the clip 11 not only serve to secure the clip to the filing tray but also provide a means whereby the sides 8 of the tray are secured to the end thereof.

70 The front of each of the filing trays is cut away at its middle portion and the two ends 14 thereof are of a less height than the sides 8 in order to facilitate the removal or placing in position of the prescriptions or data slips 12. In the present instance these front portions 14 are 75 provided with tags 15 designed to receive the numbers of the data slips within the tray, the said data slips being numbered consecutively before being filed. The bottom 7 is also cut away as indicated at 16 adjacent the front of the tray in order to provide clearance space 80 to enable the thumb to readily run over the edges of the data slips in order to locate the slip bearing the desired number.

In using the filing device the various trays 5 are filled 85 consecutively with the prescriptions or data slips and are then replaced in their respective positions within the filing case 1. When employed by druggists for the filing of prescriptions it will be readily apparent that the tray being filled can remain upon the desk and that the various prescriptions can be readily inserted under 90 the spring clip 11 as received, thereby obviating likelihood of loss and reducing the labor of indexing and filing to a minimum. At the same time the various prescriptions are so filed that any one of them can be instantly located when desired and can be removed 95 bodily from the filing tray and carried from place to place during the filling of the prescription if found desirable. In this connection it might be stated that in removing one of the prescriptions it is desirable that the prescription immediately below be slightly displaced in order to facilitate the replacing of the said prescription.

100 Instead of forming the filing tray by bending as heretofore described, the same may be stamped from sheet material or formed in any other conventional 105 manner.

Having thus described the invention, what is claimed as new is:

1. In a device of the character described, the combination of a tray comprising an end and sides, and a spring clip carried by the tray and normally pressing toward the bottom thereof, the said spring clip serving as a means for connecting the sides and ends of the tray.
2. In a device of the character described, the combination of a tray comprising sides and an end, the sides carrying extensions bearing against the end, and a spring clip secured to the end and also serving as a means for fastening the before mentioned extensions to the end.
3. In a device of the character described, the combination of a tray comprising sides and an end, the said sides carrying extensions fitting against the end, and a U-shaped spring clip, the opposite arms of which are secured to the end of the tray and also serve as a means for securing the before mentioned side extensions to the said end.
4. In a device of the character described, the combina-

tion of a tray comprising an end and sides, the said sides carrying extensions bearing against the end, and a spring clip comprising arms which are coiled at a point adjacent the end, extend downwardly along one face of the end, pass through the end and the said extensions, and then extend downwardly on the opposite face of the end. 20

5. In a device of the character described, the combination of a filing case formed with a series of spaced partitions provided with corresponding guide ways, a series of filing trays provided with outstanding flanges fitting within the guide ways, each of said trays comprising an end 25 and sides, and a spring clip carried by each of the trays and serving as a means for fastening the sides to the end. 30

In testimony whereof we affix our signature in presence of two witnesses.
